UNITED STATES PATENT OFFICE.

ALDEN BLOSSOM, OF NEWTON SQUARE, PENNSYLVANIA.

DEVICE FOR REGULATING TEMPERATURE.

1,391,935.

Specification of Letters Patent. Patented Sept. 27, 1921.

Application filed March 12, 1921. Serial No. 451,703.

To all whom it may concern:

Be it known that I, ALDEN BLOSSOM, a citizen of the United States, residing at Newton Square, in the county of Delaware and State of Pennsylvania, have invented certain new and useful Improvements in Devices for Regulating Temperature, of which the following is a specification, reference being had to the accompanying drawings.

This invention relates to certain improvements in devices for regulating temperature and has relation more particularly to a device of this general character under thermosstatic control, and it is an object of the invention to provide a compartment, such as an incubator, having a plurality of openings in communication with the atmosphere, together with means for regulating or controlling the flow through said openings.

It is also an object of the invention to provide a compartment, such as an incubator or the like, with a plurality of openings in the upper portion thereof in communication with the atmosphere, one of said openings being larger than the remainder, together with automatic means operating to control the flow through said openings.

Furthermore, it is an object of the invention to provide a compartment, such as an incubator, with an air circulating chamber in the upper portion of the compartment, together with automatic means for controlling circulation of air through said chamber in order to maintain an even temperature within the compartment.

The invention consists in the details of construction and in the combination and arrangement of the several parts of my improved device for regulating temperature whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein;

Figure 1 is a vertical sectional view illustrating a device for regulating temperature constructed in accordance with an embodiment of my invention;

Fig. 2 is a view similar to Fig. 1 illustrating a further embodiment of my invention; and

Fig. 3 is a view similar to Fig. 1 disclosing a still further embodiment of my invention.

As disclosed in Fig. 1, C denotes a compartment, such as comprised in an incubator or the like, and which is provided in its top walls with the openings 1 and 2, the opening 1 being larger than the opening 2 so that the desired circulation of air within the upper portion of the compartment C is materially facilitated, as the opening 1 serves as an eduction opening and the opening 2 provides an induction opening.

Arranged within the upper portion of the compartment C is a horizontally disposed frame 3 having disposed thereover a lamination 4 of muslin or other textile material, said lamination 4 providing an upper air chamber A. Arranged within the chamber A are the heating elements 5, such as steam pipes or the like. By the provision of lamination 4, the air is caused to circulate from the openings 2 and 1 without coming into contact with the eggs arranged within the trays 6 positioned within the lower chamber B of the compartment C.

Arranged upon the top wall of the compartment C at a point substantially midway of the openings 1 and 2 is a block 7 provided with an upstanding pivot or fulcrum member 8. Secured to and depending from the block 7 is a tubular member 9 of a length to intersect the chamber A and to terminate within the upper portion of the chamber B.

Extending laterally from the lower portion of the member 9 is an arm 10 terminating in a depending extension or arm 11. 95 Pivotedly engaged with the lower or free end portion of the arm 11 is a rod or arm 12, the opposite end portion of said rod or arm 12 being pivotally engaged with the lower end portion of a vertically disposed rod 14. The rod 14 extends upwardly through the tubular member 9 and terminates a desired distance above the block 7.

15 denotes an elongated rod slidably disposed through a block or sleeve 16, said rod 15 and block or sleeve 16 being held in fixed relation through the instrumentality of the binding screw 17 or the like. The block or sleeve 16 rests upon the pivot or fulcrum member 8 whereby the rod 15 is 110

supported for swinging movement in a vertical direction.

One end portion of the rod 15 has operatively engaged therewith a depending stem 18 provided at its lower end with a substantially conical-shaped valve member 19. The valve member 19 coacts with the opening 2 from below and serves to regulate the flow through the opening 2. The opposite end 10 portion of the rod 15 has operatively engaged therewith a disk 20 which coacts from above with the opening 1 to regulate or control the flow through said opening.

The upper portion of the rod 14 is operatively engaged, as at 21, with the rod 15 so that as the rod 14 moves upwardly or downwardly the rod 15 will be correspondingly rocked.

22 denotes a thermostat arranged and supported between the arm 10 and the rod 12. When the temperature within the compartment C, or more particularly the chamber B, rises above a predetermined degree, as 103° F., the expansion of the thermostat 22 will result in a downward movement of the rod 14 causing the valve member 19 to be lowered and the disk or valve member 20 raised, resulting in a rapid circulation of air in the chamber A through the openings 2 and 1, 30 the heated air escaping through the opening 1 and the cool air entering through the opening 2. As the temperature within the chamber B lowers, the thermostat 22 will contract, resulting in an upward movement of the rod 14 with the consequent raising of the valve member 19 and lowering of the valve member or disk 20, so that the flow of air within the chamber A being retarded whereby an even temperature, preferably 103° F., 40 is maintained within the chamber B.

Adjustably mounted upon the rod 15 and preferably on the end portion thereof adjacent the disk or valve member 20 is a poise 23 which provides means to assure the 45 requisite balance of the rod 15.

In the embodiment of my invention as illustrated in Fig. 2, the means for controlling or regulating the flow of air through the upper chamber A is the same as has been hereinbefore described with respect to Fig. 1 except that the valve 19' coacting with the induction opening 2 also cooperates with the delivery end of a pipe or conduit 24 leading within the chamber A from a 50 point exterior of the compartment C and whereby additional cool air may be delivered within the chamber A. The eduction or delivery end 25 of the pipe 24 is so formed or inclined as to conform to the periphery of the valve member 19' so that said member 19' in addition to regulating or controlling the flow of air through the opening 2 also coacts for the same purpose with the pipe 24.

In the embodiment of my invention as 65 illustrated in Fig. 3, the cool air is ad-

mitted within the chamber A through the pipe 24' and the flow through said pipe 24' is controlled or regulated by the flat valve 26 carried by the eduction or delivery end of the pipe 24'. Operatively engaged with 70 the flat valve 26 is the stem 18' carried by the adjacent end of the rod 15'. The rod 15' is supported and operated in the same manner as has hereinbefore been set forth with respect to the rod 15. The parts illustrated in Fig. 3 similar to the parts disclosed in Figs. 1 and 2 are identified by the same reference characters.

From the foregoing description it is thought to be obvious that a device for regulating temperature constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a compartment, a partition of textile material dividing said compartment into an upper chamber and a lower chamber, an air inlet opening and an air outlet opening in communication with the upper chamber, valves for controlling the flow through said openings, a thermostat within the lower chamber, and means coacting with the thermostat and the valves for automatically moving the same relative to the coacting openings.

2. A device of the class described comprising a compartment provided with an air outlet opening and a plurality of air inlet openings, a valve coacting with the air outlet opening, a single valve coacting with and common to all of the air inlet openings, and automatic means for moving said valves with respect to the openings coacting therewith.

3. In combination with a compartment, a partition of textile material dividing said compartment into an upper chamber and a lower chamber, an air inlet opening and an air outlet opening in communication with the upper chamber, valves for controlling the flow through said openings, a thermostat within the lower chamber, and means coacting with the thermostat and the valves for automatically moving the same relative to the coacting openings, the air outlet opening being of a size larger than the air inlet opening.

4. A device of the class described comprising a compartment provided in its top

with an air outlet opening and with an air inlet opening, an induction pipe for air extending within the compartment and terminating in close proximity to the air inlet opening in the top of the compartment, a valve coacting with the air outlet opening, a single valve coacting with and common to

the air inlet opening and the discharge end of the air induction pipe, and automatic means for moving said valves. 10

In testimony whereof I hereunto affix my signature.

ALDEN BLOSSOM.
